UNITED STATES PATENT OFFICE.

CHARLES H. FRY, JR., OF BELLAIRE, OHIO, ASSIGNOR OF SEVEN-NINTHS
TO CHARLES S. S. BARON, JOEL M. MARING, LAWRENCE A. FLETCHER,
THOMAS F. HART, AND CHARLES H. TALLMAN, OF SAME PLACE.

LANTERN.

SPECIFICATION forming part of Letters Patent No. 239,240, dated March 22, 1881.

Application filed January 17, 1881. (No model.)

To all whom it may concern:

Be it known that I, CHARLES HENRY FRY, Jr., a citizen of the United States, residing at Bellaire, in the county of Belmont and State 5 of Ohio, have invented new and useful Improvements in Lanterns, of which the following is a specification.

I have improved the lantern of that class in which a chimney is used of a height less 10 than that of the globe. The short chimney is supported by a foraminous band placed around the burner-cone; and as such chimney has no support at its top I provide means for securing it to the foraminous band, so that the lantern can be swung and suddenly raised and 15 lowered without danger of displacing the short chimney. In connection with such chimney I use a perforated band supporting the globe, a dome without interior cap, and an air down- 20 take around the foraminous band at the base of the chimney, the said perforated globe-band serving to supply air to the burner-tube through the downtake, to the combustion chamber or chimney through the foraminous band, 25 and to give an upward draft in the globe, so that in swinging the lantern the flame cannot be extinguished, while under a sudden descent of the lantern the upward rush of air in the globe-chamber is met by descending currents 30 from the dome-openings, and the flame will be unaffected by such movements. Under a sudden ascent of the lantern the air-currents entering the dome will be diffused in the globe-chamber, and there will be no return drafts 35 and currents through chimney and globe. The draft gives a steady and bright flame, and it cannot be extinguished in any use of the lantern.

Referring to the accompanying drawings, 40 Figure 1 represents a vertical section of a lantern embracing my improvements; Fig. 2, enlarged detail views, showing the means of securing the short chimney upon its foraminous supporting-band; and Fig. 3, a top view of the 45 globe-band, showing the inward projections of the chimney-band, and a bottom view of the chimney, showing the notched rim.

In a patent granted to me November 23, 1880, I used a long chimney with top fasten-

ings and a ventilator-cap within the dome; 50 and my present improvements are designed more especially to produce a cheaper lantern with a short chimney serving only to give steadiness to the flame. The cup parts are constructed the same as in my said patent, so as 55 to form an air downtake or passage, *a*, surrounding the base of the burner-cone *b*, and communicating with an annular space, *c*, for the supply of air beneath the burner. In forming this air-downtake the cup-ring *d*, the 60 perforated globe-band ring *e*, and the skirt *f* surrounding the burner-tube and depending from the burner-cone co-operate to supply the flame-tube under the cone with fresh air, while the foraminous band *g*, which supports the 65 short chimney *h*, supplies fresh air to the flame and draft to the chimney. The foraminous band *g* is arranged in a horizontal plane with the perforated globe-band *i*; and, while supporting the short chimney in place over the 70 burner-cone, it also serves to prevent sudden puffs of wind striking the flame through the openings in the globe-band.

The chimney may be placed on the inside or on the outside of the band *g*; but, in whichever way, it is secured therewith so that it cannot become displaced in swinging or handling the lantern. A close fitting with the band is not sufficient for this purpose, and besides, such close fitting is liable to break the chimney. 75 A simple form of such fastening is made by a corrugation, *s*, around the band *g*, so as to form a seat for the chimney, and projecting lips *r*, at the top edge of the band, with corresponding notches *u* in a rim-projection, *v*, at 80 the lower edge of the chimney, to form locks to hold it securely.

In placing the chimney upon the band the lips *r* and notches *u* are brought coincident, the chimney pressed down upon the corruga- 90 tions *s*, and then turned to make the lock. The foraminous band is secured to the globe-band by arms *w*, secured to the globe-band ring.

The dome *x* has no interior obstruction, and, 95 by its perforations *z*, affords free circulation of air between it and the top of the short chimney, preventing the undue heating of the dome

and any direct downward draft in the chimney.

I use a perforated band for the globe because it answers the same purpose as an annular opening and makes a safer support for the globe than clamping it upon the ends of wire supports. The perforated band is also better in excluding rain than an open space above the top edge of the globe-band; and I find that the perforated globe-band and the foraminous chimney-band give the required draft, both to the globe and to the chimney, in expelling the hot air from both through the dome-openings. The non-perforated part of the globe-band is fitted and secured within the cup-band in the usual manner, and the lantern is otherwise provided with the proper appliances.

I claim—

The means, substantially herein described, for locking the short chimney upon its foraminous supporting-band and within the globe, consisting of the corrugated seat *s* and the projections *r*, formed upon said band, and corresponding notches *u*, formed in a base-collar of the chimney, substantially as described. ²⁰ ²⁵

In testimony whereof I have hereunto set my hand in the presence of two subscribing witnesses.

CHARLES H. FRY, JR.
